UNITED STATES PATENT OFFICE.

ANDREW H. BERGMANN, OF NEW YORK, N. Y.

TOY-HOUSE CONSTRUCTION.

1,425,166.

Specification of Letters Patent. Patented Aug. 8, 1922.

Application filed January 31, 1921. Serial No. 441,342.

To all whom it may concern:

Be it known that I, ANDREW H. BERGMANN, of the borough of Manhattan, in the city, county, and State of New York, have 5 invented certain new and useful Improvements in Toy-House Constructions, of which the following is a specification.

This invention relates in general to combined playthings and educational devices.

10 It more especially appertains to a knock-down toy log-cabin.

One of the objects of the invention is to provide an improved device of the character described affording a miniature reproduction 15 of a log-cabin such as was inhabited by early settlers or pioneers.

Another object is to produce a device of the nature set forth capable of having the parts thereof securely joined to one another 20 so as to form a self-sustaining structure which when required may also be taken apart and stored within a container of small compass.

A further object is the provision of a device 25 of the type specified, wherein the receptacle in which the disassembled structural units are stored may be used as a foundation for the erected structure, thus enabling the ensemble to be moved about as a whole without danger of collapsing.

Still another object is the production of a device of the class mentioned, including a joint for the corners of the structure embodying a novel form of interengaging mortise and tenon that will so securely connect 35 with one another as to require no additional means to keep the parts together.

A still further object in producing a device 40 of the species referred to, is so to construct and arrange the elements composing the joints as to permit the same to be incorporated in log members of round or any other sectional configuration.

An additional object is to supply a device 45 of the genus alluded to comprising a minimum number of parts, plain, durable and amenable to low cost of manufacture, as also easily assembled in a manner that will be clearly understood by the average child 50 without demonstration, simply by following directions furnished.

Other objects and advantages of the invention will become apparent as the specification proceeds.

55 With the aforesaid objects in view, the

invention consists of the novel combinations and arrangements of parts hereinafter described in their preferred embodiments, pointed out in the subjoined claims, and illustrated on the annexed drawing, where 60 in like parts are designated by the same reference characters throughout the several views.

In the said drawings:—

Figure I is a perspective view of this improved toy-cabin, shown assembled upon the cover of its container, parts being broken away to expose the interior; 65

Fig. II is a transverse sectional view of the before described assemblage, the section 70 being taken irregularly through a window opening of the toy-cabin;

Fig. III is also a sectional view, like the one last named, but showing the dismantled elements of the structure packed in 75 the container base;

Fig. IV is a perspective view of the toy-cabin, partially assembled, showing the means for securing the door and window frames in position; 80

Fig. V is an enlarged perspective view showing in spaced superposed relation the joints for coupling the corners of the structure when the members comprising the same are of circular cross-section; and 85

Fig. VI is a similar view to the preceding, illustrating the corner connection between straight-sided members.

Concisely described, the device under consideration includes in its organization a container, as a box having a reversible lid or cover, the box being adapted to receive the several elements from which the cabin is constructed, including door, window, gable, roof and chimney elements. In the container is also stored a number of blocks representing logs of various lengths for the sides and ends of the cabin and for insertion between the door, window and corners of the structure, these logs having interengaging means formed wholly within themselves whereby the structural parts are securely bound together as the building is erected upon the reversed cover, without the use of extraneous fastenings of any kind 100 105 whatever.

The erection of the cabin, although simple and elemental in itself, calls for the exercise of moderate ingenuity, imagination and judgment, tending to inculcate skill, 110

sense of proportion and discernment in the mind of the juvenile builder, as well as affording a highly attractive form of amusement.

5 The advantages of the invention as here outlined are best realized when all of its features and instrumentalities are combined in the one and same structure, but, useful devices may be produced embodying less 10 than the whole.

It will be obvious to those skilled in the art to which the invention appertains, upon becoming conversant with the details thereof, that the same may be incorporated in 15 several different constructions. The accompanying drawings, therefore, are submitted merely as showing the preferred exemplification of the invention.

Referring now to the aforesaid views of 20 the drawings for a detailed description of the invention, the members comprising the logs employed to form the walls of the toy cabin have been generally given the reference character "A", while the different parts 25 thereof are denoted by a suffix ordinal.

Thus A¹ designates a pair of longitudinal members, the same being preferably of half round section, as shown, for a purpose that will be more fully hereinafter referred to.

30 Disposed in parallelism directly thereabove at the front of the structure are similar but circular sectioned members A² and A³, the latter being provided in its top with a lengthwise running channel 4 (see Fig. IV) 35 the object whereof will later become apparent. The rear wall is also made up of members A² of unbroken lengths.

Shorter members A⁵ are superposed upon the member A³, the same having the inner 40 ends thereof formed each with a vertical groove 6, the intent of which will be brought out farther on.

The intermediate members A⁵ and the top one of the rear members A² are in turn covered by cap members A⁷ and A⁹ respectively. The member A⁷ which is the uppermost one 45 at the front is provided with a longitudinal channel 8 in its lower face, similar but opposed to the channel 4 in the said member 50 A³. Both the cap members A⁷ and A⁹ have crosswise extending slots 10 in their upper faces, near the ends thereof, for a purpose later on pointed out.

The rear transverse wall of the toy-cabin 55 is built up wholly of members A¹¹ of the same general description as A², but relatively shorter in length than the latter, while at the opposite or front end, the structure includes through members A¹¹, one at the bottom 60 and two at the top, having interposed therebetween a plurality of shorter members A¹².

The means for joining the members of the 65 toy log-house at the corners is here shown as consisting of a recess 13 formed across

the upper half of one member near the end thereof and adapted to receive therein the lower half of the members superlying the same.

The recesses in the several logs are each 70 provided with a notch or mortise 14 and a tenon 15, so constructed and arranged that while the notch is located on the exterior side of the log member, midway between the ends of the recess, the tenon is disposed in 75 the central longitudinal plane of the member at the upper part of the recess, right angularly to the said notch, as shown most clearly in Fig. V.

The notches and tenons are interengaging 80 inasmuch as the notch in a superlying member is capable of receiving the tenon of a sublying one. It is to be noted, that the inner face of the tenon aligns with the bottom of the notch in the same member, while 85 the length and breadth of the tenon as well as the depth and width of the notch occupy each about one-third of the recess in all directions.

Notwithstanding that it is preferred to 90 construct the toy-cabin of round log members as represented in Figs. I to V, it is quite possible to make the walls of the cabin of straight sided members. This is shown in Fig. VI where rectangularly shaped recesses 95 13^a are formed in square sided members A^a, which recesses are provided with semi-circular notches 14^a adapted to take over dowel pins 15^a constituting the tenons.

By reason of the interfitting tenons and 100 notches, the members comprising the cabin walls are firmly joined to one another without extraneous means for keeping them together, while the same admits of being taken apart when the structure is to be dismantled. 105

Although the members and the joints at their intersections have been illustrated and described in conjunction with a toy house, no limitation is intended in this respect, as several other structures both in the line of 110 playthings and useful devices may be made embodying the same type of joints.

At B is indicated a window-frame element, interposed between the members A⁵, and intermediate the top and bottom ones 115 of the log members A³ and A⁷. For the purpose of securing the said window frame in position relatively to the adjacent log members, the former is furnished with a centrally arranged circumambient rib 16. 120 The vertical portions of the latter are adapted to enter the oppositely facing grooves 6 in the adjoining members A⁵, previously mentioned. The horizontal top and bottom parts of the said rib 16 are received respectively in the channels 4 and 8 of the log members A³ and A⁷, referred to hereinbefore. It will be apparent, that, due to this arrangement, not only is the window-frame B maintained in place, but the rib thereof 125 130

serves to keep the inner ends of the abutting log-members in their assigned position.

Instead of having one central rib as above described, two such ribs or flanges suitably spaced apart, can be resorted to, as has been indicated in conjunction with a door-frame element C, where 17 represents the outer molding around a door 18, and 19 the molding on the inner side of the same. Here the lengthwise extending top and bottom portions of the moldings 17 and 19 take around and are held in place by the adjacent upper and lower log members A¹¹, while the endwise abutting members A¹² are steadied by the vertically running parts of the said moldings. The door 18 may be connected to the frame element 17 by means of strap hinges 20 composed of small pieces of leather or the like. It is obvious that the cabin in question may be furnished with several doors and windows if so desired.

D and D²¹ designate gable elements for the cabin which rest with their bases on the uppermost of the log members A¹¹ at the near and far transverse walls of the toy-cabin. These gables have the bottom corners thereof received in the cross slots 10 of the cap members A⁷ and A⁹, as previously intimated.

Overlying and supported by the said gables are roof sections or elements E and E²² which are provided with lengthwise extending cleats 23 and 24 respectively, serving as stops in preventing these sections from sliding off the gables. To this end the said cleats are made to seat against the inside faces of the cap members A⁷ and A⁹. The stops 23 and 24 run preferably the entire length of the roof elements between the gables D and D²¹ and serve to keep these elements from warping out of shape. At the peak or meeting point of the said roof-sections, E and E²², are fastened, for instance to the element E and at right angles to each other, a couple of strips 25 and 26 constituting the roof ridge of the cabin.

A block element F representing the chimney is removably attached, as for example by a dowel 27 to the other one of the roof-sections E²².

The previously referred to half round basal log members A¹ are preferably secured to a cover G of a box G²³ which may constitute the foundation for the cabin when erected, and also serves as a container for the dismounted members and elements composing the structure. As represented in Fig. III, the cover G with the members A¹ thereto attached can be inserted in the container in an inverted position, so that the latter will be entirely smooth on its exterior for convenience in shipment and storage.

While certain preferred embodiments of this device have been shown and described, it will be understood that changes in the form,

arrangements, proportions, sizes and details thereof may be made, without departing from the scope of the invention as defined by the appended claims.

Having described my invention what I desire to secure by Letters Patent and claim, is:—

1. An article of the character described comprising intersecting members disposed in vertically offset relation, being arranged alternately in longitudinal and transverse directions, and a joint at the intersection of said members including a recess formed across each of the latter in one face thereof and adapted to receive the unrecessed portion of an alternate member, said recess having a notch and a tenon, the arrangement being such that the tenon of one member engages the notch in another member. 75

2. An article of the character described comprising members arranged in crossed relation adjacent to their extremities, and joints at the crossings including a transverse recess formed in each sublying member and capable of receiving substantially one half of the exterior contour of a superlying member, said recess being provided with a notch in its side and a tenon extending lengthwise thereinto, the tenon on one member being adapted to enter the notch in 95 a superposed member. 85

3. An article of the character described comprising members disposed in intersecting relation near their ends, and joints at the intersections including recesses formed transversely in said members at approximately one half the depths thereof and adapted to receive the corresponding portions of the superlying members, said recesses being provided midway of their exterior sides with notches and having at right angles thereto central tenons extending inwardly at the top, the tenons of the sublying members being capable of entering the notches in the superposed members. 100 105

4. An article of the character described comprising members located in transversely stepped relation, and joints at the meeting places of said members including recesses cut across the upper faces of the latter 115 adapted to receive an equivalent portion of the overlying members, said recesses being provided in their outer sides with notches reaching approximately one-third therethrough and having inwardly projecting tenons extending a corresponding distance from the ends of the members at the top thereof, the arrangement being such that the tenons of the underlying members are capable of entering the notches in the super- 120 125 lying members.

5. An article of the character described comprising a plurality of tiered members spaced apart vertically and horizontally to leave an opening therebetween, the members 130

forming the vertical sides of said opening having oppositely facing grooves in the ends thereof, the top and bottom members bounding the horizontal sides of the opening being provided in their opposed faces with channels coinciding with said grooves, and a frame receivable in the opening including a circumambient rib capable of

coacting with said channels and grooves, the portions of said rib engaging the channels serving to hold said frame in place within the opening, while the vertically disposed parts of the rib entering the grooves in the ends of the members are adapted to maintain the latter in position. 16

ANDREW H. BERGMANN.
